[57] CLAIM

The ornamental design for a baby shoe, as shown.

DESCRIPTION

FIG. 1 is a top and left front perspective view of a baby shoe showing my new design;

FIG. 2 is a top plan view thereof; the bottom, not shown, being flat, plain and unornamented;

FIG. 3 is a left side elevational view thereof;

FIG. 4 is a right side elevational view thereof;

FIG. 5 is a perspective view of FIG. 1 wherein the fastener strap is in an open position.
